UNITED STATES PATENT OFFICE.

FRANK C. DOBLE, OF WINCHESTER, MASSACHUSETTS.

INSULATING MEDIUM FOR TRANSMISSION OF INTELLIGIBLE SOUNDS.

Application filed August 2, 1920. Serial No. 400,741.

To all whom it may concern:

Be it known that I, FRANK C. DOBLE, a citizen of the United States, residing at Winchester, in the county of Middlesex and 5 State of Massachusetts, have invented new and useful Improvements in Insulating Mediums for Transmission of Intelligible Sounds, of which the following is a specification.

10 The present invention is concerned with the electrical transmission of speech, and other intelligible sounds or audible signals, and with protection for the persons who receive or transmit such sounds and signals 15 from the harmful effects of excessively high electrical potential conditions in the circuits and other electrical conductors employed in electrical sound transmission. Among the modes of transmitting sounds electrically 20 contemplated in the foregoing statement are included telephonic speech transmission over metallic circuits, wireless telephony, wireless telegraphy, and the like. With the ordinary low tension telephone systems possibility, 25 however remote, exists of the line becoming excessively charged, as by lightning discharges, accidental connection with high tension circuits and currents, etc.; and there are other telephone systems, called high tension 30 systems, of which the line wires are run in close proximity to high potential electric power transmission lines, which are liable to receive high potential charges directly or inductively from the adjacent power transmission line, of a nature and from causes 35 well known to those acquainted with the art. In the practice of radiotelegraphy the operator receives conventional signals audibly through a telephonic receiver; and in 40 radio telephony he both receives and transmits articulate speech sounds through instruments similar to the receiver and transmitter of ordinary telephone equipment. In either case electrical storms and lightning 45 discharges are liable to create high potentials in the antennæ of the radio equipment. All such electrical disturbances are dangerous to persons using the apparatus at the time when they occur, and have on many 50 occasions caused death or serious injury to such persons.

It is the object of the invention to protect the operators of such systems and ap-

paratus (and by the term "operator" as used in this specification I mean any person who uses the system) from harm from high potential conditions which may occur in the conductors of the system at the time of use, by an insulating medium which is also capable of efficiently conveying intelligible 60 sounds; and the invention consists in such a medium, as well as in the combination thereof with the electrical sound transmission apparatus in connection with which it is used. I have discovered that the medium 65 in question causes certain improved effects in the transmission of sound, later explained in detail, and therefore assert that part of the invention or discovery which I desire to protect consists in the hereinafter described 70 means for producing such effects, and all equivalents of such means.

The following specification, in connection with the drawings forming a part thereof, 75 discloses what at present I consider the best form or embodiment of my invention, and certain illustrative uses thereof, although I have not attempted therein to describe all its possible uses. In the drawings,

Figure 1 is a side elevation of a combined unit apparatus embodying the invention.

Figure 2 is a left hand end view thereof.

Figure 3 is a longitudinal section on an enlarged scale, the terminal fitting being in 85 elevation.

Figure 4 is a cross section of the box element of the unit containing telephonic apparatus.

Figure 5 is a plan view and partial section 90 of the terminal fitting.

Figures 6 and 7 are perspective views showing different modes of connecting the unit in a telephone line.

Figure 8 is a diagram showing two telephone sets including the novel features of the present invention in connection with a telephone line.

Figures 9 and 10 are diagrams illustrating the use of the invention to protect operators 100 of wireless telegraph and wireless telephone apparatus, respectively.

Figure 11 is a diagram illustrating the use of my invention as a relay for transmission of speech between separate and unconnected telephone lines.

The same reference characters indicate the same parts in all the figures.

I will first describe the construction and parts of the combined apparatus shown in detail in the drawings, and then explain its uses and principles. 1 represents an elongated sound-transmitting insulating body having two wholly enclosed and separate passages or bores, 2 and 3, extending through it from end to end, and to which at one end is connected a mouth piece 4 in exclusive communication with the passage 2 and an ear piece 5 in separate communication with the passage 3. Any material which is at the same time an insulator and a good sound conductor when fashioned in hollow form may be used for making the body 1, and of the materials having these characteristics I prefer wood on account of its other useful qualities of strength and light weight. When wood is used it is preferably impregnated with paraffin, or otherwise made repellent to water, in order to avoid danger of its insulating property being lessened by absorption of moisture. This body is the insulating medium referred to in the introductory part of this specification. Structurally it is essentially a tube, and will be for convenience generally referred to as such in the following description. It may also be considered as a double tube or as two tubes combined in one structure, and indeed for many purposes two separate tubes are equivalent to such double tube; as also is the combination of one or more tubes, which in themselves each inherent stiffness or rigidity, with an extraneous member or structure possessing sufficient stiffness and so associated with the tubes as to serve the purposes set forth in this specification.

The mouth piece and ear piece may be arranged at the end of extension tube leading from the bores of the double tube, of such lengths and disposition that said pieces may be placed respectively in front of the mouth and beside the ear of the operator at one time; and preferably they are parts of an integral metal casting, or other formed body suitably connected, detachably or permanently, to the tube 1 and having integral passages. Practically it is necessary that the passageways through the insulating medium to the two terminals, constituted by the mouth pieces and the ear piece respectively, be entirely separate from one another, without intercommunication or any lateral outlet, in order to avoid confusion of the sound waves conducted to and from the several terminals, or loss of clearness or loudness of the sound. But I may insert diaphragms at suitable points to exclude moisture, etc. from the passages, since the value of diaphragms for such purposes may offset whatever slight obstruction they may

oppose to sound transmission. 4^a and 5^a in Fig. 5 indicate such diaphragms in the terminal orifices.

At the opposite end of the tube 1 from the terminals, the passage 2 is connected to a telephonic transmitter 6, and the passage 3 is connected to a telephonic receiver 7. These last may be identical with any standard transmitter and receiver used in common telephone practice, or they may be of special design. For convenience they are secured in a box or case 8 which is connected to the tube 1 in a mechanical unit structure. Short tube connections 9 and 10, which may be flexible or rigid, continue the passage 2 exclusively to the sound-admitting aperture of the transmitter, and the passage 3 exclusively to the sound-emitting aperture of the receiver, in order to complete the exclusive sound channels from the transmitter and receiver to the mouth piece and ear piece respectively. The same box preferably contains also a battery, induction coil, conductors, and switch; and also preferably carries protections such as are usually provided in telephone circuits and more particularly those used with high tension telephone systems, to equalize the potential in both sides of the line. 12 represents the battery, a common dry cell type, and 13 represents the induction coil. The terminals or poles of the battery are in contact with two separated and insulated contact pieces 14 and 15, from one of which a conductor such as 16 leads to the transmitter and from the other of which a conductor such as 17 leads to one end of the primary winding of the induction coil. Conductors such as 18 and 19 lead respectively from opposite sides of the switch to the transmitter and to the outer end of said primary winding. The switch here shown consists of two separated plates 20 and 21 fixed to the rear wall of the box at opposite sides of a hole 22 in such wall, through which a plug may be inserted to bridge the gap between the plates. But any other type of switch may be there used. The receiver is connected by a conductor 23 with one terminal of the secondary winding of the coil 13, and by a conductor 24 with an external binding post 25 on one side of the box; and the other terminal of said secondary winding is connected by a conductor 26 with an external binding post 27 at the opposite side of the box. External conductors 28 and 29 pass from these binding posts and are adapted to be connected directly or indirectly to the line wires of the telephone system. The apparatus just described may be used as a portable set or as a permanent installation; and when adapted for portable use, the conductors 28 and 29 preferably have substantial strength and are provided at their ends with hooks 30 and 31 whereby they may be

hung directly upon the wires of a telephone line (Fig. 6), or like hooks so suspended may be connected with the said binding posts by flexible conductors as shown in Fig.

5 7. Otherwise, equivalent conductors of any nature may be used.

The equalizing protection previously referred to is herein illustratively shown as furnished by a vacuum tube 33 and a horn gap 34 arranged in parallel between the external conductors. The vacuum tube is mounted in any convenient way inside the box on a side wall thereof, and one end is connected electrically with an external plate 35 in which the binding post 27 is set, while its other end is connected with a conductor 36, conveniently a flat strip of copper, passing around the box to a plate 37 in which the binding post 25 is set. The 10 horns of the horn gap are mounted adjustably on the top wall 38 of the box and are connected to conductors 39 and 40 which pass along said wall into contact with the plates 35 and 37. Fig. 8 represents diagrammatically, for greater clearness, the elements of two instruments such as that just described connected in a line; and in said figure the same reference characters distinguish the diagrammatic representation of said elements, while *p* and *s* indicate the primary and secondary windings of the induction coil. The apparatus thus shown is essentially like the ordinary bridging telephone set, but the showing is for illustration only, 15 and other telephone connections and means of protection can be used as well, and installed in any suitable way or arrangement, whether that shown in the present drawings or otherwise without departure from the 20 central idea of the invention which I desire to protect, as set forth in the appended claims.

Also the two passages 2 and 3 are there shown as separate tubes, both for convenience in the diagram and to indicate that two tubes are in principle equivalent to a structurally unitary double tube.

In the combination thus described, the tube 1 is a sound conducting and electrically insulating medium enabling the operator to transmit and receive articulate speech and other sounds through a telephone system without danger. It protects the operator against passage through his body to the 50 earth of electrical charges and currents at high potential from the telephone line; the degree of protection thus given being a function of the length of the medium. I have found that a length of six feet of properly 55 impregnated wood is sufficient, with an ample factor of safety, to protect the operator against discharge of potentials up to 60 30,000 volts.

I have found also that the medium gives 65 improved acoustical effects both in sending

and receiving sounds, whether the medium is a tube with a double bore, or one with a single bore. These improved effects consist both in amplification of the sound transmitted in either direction, and in an increase in the range of vocal pitches possible to be used without production of disagreeable and confusing reverberations or resonances, when the diameter of the bore and its length are in the proper ratio. In other 70 words, the speech transmission is made both louder and clearer with the aid of this medium properly proportioned than with the unaided telephone set. Without attempting at the present time to state exact dimensions or proportions, or to formulate a general law applicable to the subject, I may state the fact that I have obtained the results mentioned with tubes having a bore of one-half inch and lengths between three 80 and ten feet, and also with tubes between ten and twenty feet in length having a bore of three-fourths of an inch. The values just given indicate approximately the correct 85 proportions necessary to obtain the improved acoustical effects described.

The tube or passage having the characteristics substantially as hereinbefore set forth, that is, the tube or passage which extends from the telephonic receiver to the 95 ear piece, has the very important and valuable effect of diminishing to a safe degree the acoustical shock which occurs when a sudden extreme impulse is imparted to the diaphragm by electrical waves of high potential and high frequency on the line. Such waves are imposed on the telephone line when an arcing ground or flashing of current around an insulator, or analogous accident, occurs in a neighboring high potential 100 electric transmission line; and are also caused by electrical storms and lightning discharges. Electrical waves of the sort here referred to are also called "steep front" waves. The effect of such waves upon the 105 telephonic receiver is to give the diaphragm a sudden violent oscillation which, when the ear of the operator is held in the ordinary close proximity to the receiver, causes a violent shock upon the ear. In extreme cases this shock may burst the ear drum; and in any case it causes a nerve shock, and if repeated frequently enough it produces a profound nervous reaction in the operator. This danger to operators is so serious that the operation of telephone systems has been discontinued during electrical storms in preference to requiring the operators to expose themselves to that danger. The tube 110 of my invention, by interposing an air column between the receiver and the operator's ear, so softens the impulse delivered by the violent action of the diaphragm in the above described circumstances that 115 danger of harm to the operator from these

causes is avoided, and in consequence telephone lines may be continued in operation with the aid of the medium embodying this invention throughout the course of all such disturbances.

So far as I am aware, the use or combination of a sound conducting hollow medium of this nature with an electrical sound transmission instrument for and with the production of such improved effects is a new invention or discovery, for which I claim protection herein. Such mediums adapted for the particular purpose last discussed may be used with telephones of any nature, with or without the feature of insulation from electrical discharge, but preferably with that feature, all within the scope in which I claim protection.

The term "electrical sound transmission instrument" as here used, and likewise such terms as "electrical sound converting device," "electrical telephonic device," or words of similar import later used in this specification, include any means by which sound waves are transformed into electrical undulations, or vice versa, and specifically include all forms of telephonic transmitters, so-called, and telephonic receivers, so-called. Such instruments are forms of apparatus which are adapted to effect conversion between electrical effects and audible effects; or in other words to convert an electrical effect into sound, or an audible effect into an electrical effect. So far as concerns the broadest scope in which I claim patent protection for the invention embodied in the insulating medium I do not limit such protection to so-called telephonic transmitters and receivers, but includes also such medium combined or applied for use with possibly other sorts of apparatus by which conversions of the character indicated may be made.

The combined apparatus with telephone set and sound-transmitting insulating medium may be used in all conceivable relations and positions. It may be carried about and cut in on a telephone line anywhere and in various ways, some of which are illustrated in the drawings. In a permanent installation perhaps the most satisfactory way is to mount the telephone on a wall with the insulating tube projecting horizontally at a convenient height for the operator, and the outer end of the tube with its terminal pieces may be enclosed in a booth; but these arrangements are optional and may be departed from at will.

Some of the possible other uses of the sound-transmitting insulating medium are shown in the drawings. Fig. 9 shows its use for protecting a wireless telegraph operator. Such operators receive signals through a pair of receivers held against the

ears by a headband. The receivers of such pair and the headband are designated conventionally as 41, 42, and 43, respectively. During electrical disturbances the operator cannot with safety allow the receivers to remain on his head, and at such times he is, of course, incapable of receiving signals. By connecting insulating sound transmission mediums 44 and 45, having ear pieces, to the receivers, the operator is enabled safely to listen for signals throughout an electrical disturbance. The same thing may be accomplished with wireless telephone apparatus, as shown in Fig. 10 by connecting such a medium 46, equipped with a mouth piece 47 to the transmitter 48 of the set, and by connecting the same sort of medium, 49, equipped with an ear piece 50, to the receiver 51. In the latter case the mediums 46 and 49 may be combined in a single unit tube structure having two bores, like that first described. I have not attempted here to show the complete circuits and equipment of the wireless telegraph and telephone apparatus, for the use of my sound-transmitting protection therewith does not involve any modification therein. In any other situation where a person is required to listen to sounds emitted from electrical apparatus, protection may be secured by like means in essentially the same way.

Still another use of the invention is that of a relay adapted to connect telephones in different lines acoustically but without electrical connection, and in fact with insulation preventing current flow from one line to the other. Fig. 11 shows diagrammatically an installation organized for that purpose, where 52 and 53 are the transmitter and receiver of a telephone set in one line L, and 54, 55 are the transmitter and receiver of a telephone in a different line L'. An insulating tube 56, or equivalent sound conductor, passes from the transmitter 52 of one instrument to the receiver 55 of the other instrument, and a like tube or medium 57 passes from the receiver 53 of the first telephone to the transmitter 54 of the other. Thus an operator using any second telephone on the line L can hold a conversation with an operator at any second telephone on the line L'; for when electrical undulations in either line are converted into sound waves in the receiver connected in that line, such sound waves are conducted by the intermediate tube to the transmitter of the telephone in the other line, and are there transformed into electrical undulations which traverse the latter line. Laws or regulations prohibit direct electrical connection being made between certain telephone lines, as for instance between a low tension public system and a high tension system near a power transmission line, but my invention enables speech to be transmitted between more or less remote stations on the

different lines without putting either the low tension system or its users in danger from the high potential conditions which are more liable to occur in the high tension system. In the case last described the sound conduits (56 and 57) may be grounded at a point between their ends, if desired for additional protection. And in any case, the conduit or tube or equivalent medium may be made of sufficient length to obtain the needed insulating effect, being possibly constructed of separate lengths joined together end to end when great length is required, and may be grounded from any point and in any use where grounding would be an additional safeguard to the operator or apparatus.

I have intended to make it clear from the illustrative uses described in the foregoing specification that the fundamental idea of the invention is not limited as to the particular construction of the electrical sound converting device (transmitter, receiver, or the like), with which my sound-conveying insulating medium may be combined and used. I desire now to state further that such medium is not necessarily required to be made as a tube, in the narrowest definition of that word, but that it may have any form which enables it to conduct sound intelligibly. The term "tube" as herein used includes any hollow body or shell having a passage adapted to conduct sound waves through it, whether such shell and passage are regular or irregular in shape and dimensions, provided always that the medium or tube is additional to the electrical device proper, and (except as to those uses previously described which may be served without insulation) is an insulating protector capable of preventing flow to ground of high tension electrical potential. To be an insulating protector within the meaning of this specification, the medium must be capable of withstanding, without breaking down a sustained electrical stress of at least one thousand volts pressure (root mean square sine wave value) at any frequency.

What I claim and desire to secure by Letters Patent is:—

1. The combination with an electrical apparatus adapted to effect conversion between electrical and audible effects, of a combined insulating sound conducting medium and barrier including a channel for conveyance of sound waves, constructed and arranged to maintain safe separation between said apparatus and all parts of the person of an operator using it.

2. The combination with electrical apparatus adapted to effect conversion between electrical and audible effects, of a structure including a sound conducting channel and rigid supporting material, said channel having an orifice designed to be placed beside

the head of the operator, and the rigid structure being arranged to maintain said orifice at such a distance from the electrical apparatus that in the normal use and handling of the combined instruments the operator is 70 safely removed from the effects of high voltage at the electrical apparatus; said structure being of insulating material.

3. The combination with an electrical apparatus adapted to effect conversion between 75 electrical and audible effects, of an insulating sound conducting tube having an orifice adapted to be placed besides the head of an operator and being arranged to receive sound waves from said electrical device; said tube being of a length between the said orifice and said apparatus greater than the length of a normal adult person's arm, and being further constructed to maintain a separation between said orifice and the electrical apparatus of a distance greater than the normal reach of an operator when placed with his head beside said orifice.

4. The combination with an electrical device for converting electrical effects into sound, of a rigid insulating structure including a channel arranged to conduct sound from said electrical device and having an orifice adapted to be placed beside the ear of an operator, arranged and extended from said device to such a distance that all parts of the operator's person using it are safely separated and insulated from the effects of electrical stress at high tension in said device.

5. A means for protecting an operator using an electrical telephonic instrument from the effects of high potential electric stress in such instrument and in the vicinity thereof, which comprises an insulating structure including a sound conducting passage having a terminal orifice, of such length and so extended that the orifice is at a greater distance from the telephonic device than the distance between the ear of the operator 110 using it and the end of his extended arm.

6. The combination with an electrical apparatus adapted to transform sound waves into electrical effects, of an insulating structure having a sound conducting channel with an orifice adapted to be placed in front of the mouth of an operator, said structure having such length and arrangement that said orifice is separated from said electrical device by a distance greater than that to which the operator using it is able to reach when placed with his mouth in position to speak into said orifice.

7. The combination with an electrical apparatus adapted to convert sound waves into electrical effects, of an insulating medium including a channel for conduction of sounds, said channel leading from the electrical apparatus and having an orifice, and said insulating medium being further con-

structed and positioned to maintain a distance between the orifice and all parts of the person of an operator placed in position to speak into said orifice, sufficient to insulate 5 such operator from the effects of electrical stress at high tension in and adjacent to said apparatus.

8. A means for making safe the use of 10 telephonic apparatus in the vicinity of high potential electric currents, comprising the combination with an electrical telephonic device adapted to be placed in position to receive electrical current or charge, of an insulating holder of substantial length on 15 which said apparatus is mounted and by means of which it can be placed in current receiving position, and a sound-conducting passage in association with said holder the walls of which are of electrically non-conductive material throughout the greater part 20 of their length, said passage being in sound-receiving proximity at one end to said telephonic device, and having an orifice remote from said telephonic apparatus through 25 which sound waves may pass.

9. An electrical telephonic device combined with a holder of substantial length made of insulating material on which said device is mounted, said holder having a 30 sound-conducting passage through it terminating in sound-receiving proximity to said device, and an ear piece in connection with the end of said passage remote from the telephonic device and adapted to be placed beside the ear of an operator; said holder adapted for manipulation to place the telephonic device in position to receive current from a source of electricity and having a 35 length sufficient to protect the user holding it at one end from the current in a high potential conductor with which its other end may come into contact.

10. A means for making safe use of an 40 electrical apparatus for the conversion of electrical into auditory effects, in the vicinity of high potential electric currents, comprising the combination with such an electrical apparatus adapted to be placed in position to receive electrical current or 45 charge, of an insulating holder on which said apparatus is mounted, said holder being portable and movable by an operator and having a length and insulating strength sufficient to safeguard the operator from the 50 effects of high tension electrical stress when the operator holds said electrical apparatus in the vicinity of a conductor of high potential electric current and the holder structure being associated with a sound conducting passage the walls of which are of electrically non-conducting material, said passage being in sound receiving proximity at one 55 end to said apparatus and having an orifice remote from the apparatus through which 60 sound waves may pass.

11. The combination with an electrical telephonic device adapted to convert sound waves into electrical effects of a structure of substantial length made of insulating material, which structure includes strength for 70 supporting and moving the telephonic device and a sound conducting channel leading from said device, and a mouth piece in connection with the end of said channel remote from the telephonic device adapted to be 75 placed in position to receive sound from the mouth of an operator; said holder structure being movable by the operator and having a length sufficient to protect the operator holding it at one end from the current in a high 80 potential conductor with which its other end may come in contact.

12. The combination with a telephonic apparatus adapted to be used in proximity to conductors of high potential electric current, 85 of a combined holding and passage structure of insulating material and of a length so great that an operator whose head is at the remote end of said structure from the telephonic apparatus is safely distant as to all 90 parts of his person from the effects of an electrical stress at high tension in said apparatus, and said passage being in sound conducting proximity to said apparatus at one end and having an orifice at the opposite 95 end.

13. A protective telephonic apparatus comprising a box, a tube projecting from said box having two separate channels with distinct terminal orifices adapted to be placed respectively in front of the mouth and beside the ear of an operator, said tube being of insulating material, an electric telephone apparatus including a receiver and a transmitter in said box, and exclusive tubular connections joining the passages in said tube with the transmitter and receiver, respectively.

14. A telephonic apparatus comprising a receiver and a transmitter, means for holding them adjacent to one another, a tube of insulating material having two separate and exclusive passages, means connecting one of said passages exclusively to the said transmitter, means connecting the other of said passages exclusively to said receiver, and terminal fittings in exclusive connection with the respective passages.

15. A telephonic apparatus as set forth in claim 14 wherein diaphragms for excluding moisture are interposed at suitable points near the respective orifices of said passages.

16. An apparatus as set forth in claim 14 in which a box encloses the telephonic apparatus, and conductors in electrical connection with said apparatus are attached to the box and are provided with hooks enabling them to be hung on the wires of a telephone line.

17. A means for making safe the use of telephonic apparatus in the vicinity of high

- 5 potential electric currents, comprising the combination with an electrical telephonic device adapted to be placed in position to receive electrical current or charge, of an insulating medium having an interior sound-conducting passage in sound-receiving proximity at one end to said telephonic device and having an orifice remote from said telephonic device through which sound waves 10 may pass, said medium being so disposed that said orifice is at a distance from said telephonic apparatus greater than the reach of an operator when placed with his ear adjacent to such orifice.
- 15 18. A means for making safe the use of telephonic apparatus in the vicinity of high potential electric currents, comprising the combination with an electrical telephonic device adapted to be placed in position to receive electrical current or charge, of an associated holder and sound conducting tube made of insulating material, on the holder part of which association the telephonic apparatus is mounted and which the tube portion of which association said apparatus is in sound-conducting connection, said holder being operable to place the apparatus in current-receiving position, and the tube having an orifice remote from said apparatus.
- 20 19. The combination with a telephonic receiver of a sound conducting tube extend-
- 25 ing from said receiver and having an ear piece adapted to be placed beside the ear of an operator, said tube having a bore of approximately one-half an inch and a length of 35 at least approximately three feet, whereby the contained air column diminishes to a safe degree the acoustic shock carried by electrical waves of high potential and high 40 frequency on the line.
- 30 20. An electrical apparatus adapted to effect transmission between electrical and audible effects, combined with a tubular sound conductor leading from said apparatus and adapted to conduct sound waves between the same and a distant orifice; the ratio of the bore of said tube to its length being so small as to damp sound reverberations, and at the same time so large as to conduct sound without substantial diminution of the clearness and loudness of transmitted words; said ratio being within the following named limits, to wit; a bore of approximately one-half inch diameter for tubes between 3 and 10 feet in length; and 50 a bore of approximately three-fourths of an inch in diameter for tubes from 10 to 20 feet in length.

In testimony whereof I have affixed my signature.

FRANK C. DOBLE.
